UNITED STATES PATENT OFFICE.

CLEMENT V. HILL, OF TRENTON, NEW JERSEY.

REFRIGERATOR DISPLAY CASE.

Application filed December 10, 1927. Serial No. 239,142.

One of the most serious objections to refrigerator display cases with refrigeration at or near the top, is that the currents of hot air come in contact with the currents of cold air 5 in the case, whereby the warm air condenses in the cold air and this condensation settles down on the goods displayed in the case; also on the glass panels and doors of the case, especially near the top. When the doors are 10 opened the hot air rushes in the case near the top and condenses on the bottom of the drip pan; also on jambs or framework above the doors, as the cold air from the pipes or tank above comes in direct contact with the door jambs and framework above, causing considerable dampness and moisture in the case. 15 Many attempts have been made to prevent this condensation gathering on the glass, doors, frames and upper part of the case 20 like a fog, which conceals the contents of the case thereby defeating the object of display cases.

A case built with the cold reservoir at the top, having a drip pan underneath the coils 25 or tanks to catch the condensation, spreads the cold air across in the top of the case, because the cold air cannot drop down in the case on account of the pan; therefore, the air circulation is directed sidewise toward each 30 side of the case, making the front glass very cold near the top; also the doors and jambs very cold near the top. The glass either side being so cold causes a sweat on the inside glass between the two inner plates of glass. 35 In other words, the moisture in the space between the two inner glass plates condenses near the top on the inside of the inner glass. This condensation causes a moisture or foggy appearance, which is between the two inner 40 plates of glass. Now by providing the baffles, according to my invention, the warm air passes up next to the walls of the case, so the walls, doors or glass panels do not become nearly as cold, preventing the condensation 45 between the two inner plates of glass. The front of the case and the doors are fitted with two or three glass plates, and sometimes four glass plates, when a very cold temperature is desired. The baffles prevent the currents 50 or circulation of cold air from coming in contact with the walls of the case, and instead, the cold air is carried down in the centre of the case and the warm air passing up between the baffle and the wall of the case increases 55 the circulation on account of no currents of

cold air coming down in that space to retard the circulation upward.

In the drawings:

Figure 1 is a vertical transverse section of a display case embodying my invention. 60

Figure 2 is a detail view showing a modified form of baffle plates or deflectors.

The reference numeral 1 designates a display refrigerator case having the display chamber 2 provided with a perforated shelf 65 3, on which the goods are displayed. This display chamber is provided with glass panels 4 and glass panel doors 5. The case is provided with suitable insulation 6. As shown cases of this general character are converged 70 near the top so that, as a rule, there is a comparatively narrow space at the top of the case in which to position the refrigerating element in said top and get the warm air currents up there and cause the cold air currents 75 to flow down from said top. In the present instance for purposes of illustrating my invention I have shown refrigerant circulating pipes 7 in the top of the case, and positioned a drip pan 8 beneath said pipes. 80

On each side of the pipes 7 I have positioned a baffle plate 9 which extends to the top of the series of pipes and at their lower end extend below the drip pan, the lower ends being deflected inwardly as at 10. These 85 baffle plates converge toward each other from bottom to top, the distance between the lower ends of the baffle plates at the bottom being greater from the converging top side walls of the case than they are at the top, thereby 90 providing a wide open space at the bottom to facilitate the flow of warm air up between the baffles and the top side walls of the case.

These baffles 9 divide the circulation of 95 warm air and of cold air to and from the refrigerating medium. Without this division, in such a narrow space, as is found in typical display cases at the top, to get cold air down in the case and the warm air up to the refrigerating medium without the warm air 100 condensing and forming as a sweat on the glass panels is an impossibility.

Now in using my invention the baffles 9 direct the cold air down in the center of the case. Said baffles hold the cold air in a central 105 column, which passes through the shelf 3 into the lower storage compartment 11 as indicated by the arrows, thereby permitting the warm air to pass up next to the walls of the case, thence between the baffles 9 and the walls, 110

over the top of the baffles to the refrigerating medium 7.

I have found by experiment that with my invention used the walls of the case do not get 5 as cold as they do when the baffles are not used, therefore they do not sweat as much when the doors are opened, and the glass panels in the doors do not sweat.

The baffles 9 are removable and may be 10 made adjustable as to height, increasing or diminishing the circulation of air if found desirable.

You can readily see, as I said above, the 15 walls of the case do not get as cold, consequently the moisture will not condense on them nearly as much when the doors are opened, and what little moisture does condense, when the doors are opened, is soon dried off by the warm air current passing up. But, 20 without the baffles this moisture keeps gathering until the walls become very wet, which swells the doors and framework of the case and causes much dampness in the case. The sweating on the bottom of the drip pan does 25 not amount to much. The main feature of all is to keep the walls of the case from getting cold enough to condense moisture between the two inside glass; also on the jambs and walls of the case near the top. The increased circulation of air caused by the 30 baffles makes it possible to produce a dry cold air in the case; also prevents sweating between the glass and on the walls of the case.

In Figure 2 I have shown the baffle plates 35 9^a without any deflection at their lower ends.

In reference to baffles being arranged on a bevel and not exactly straight up and down, will say a baffle straight up and down could be used as well, if the case were a little wider 40 at the top. In a case narrow at the top it is

an advantage to have them near the shape of the walls of the case, as shown in my drawings. Of course, a person could make the same case a little wider at the top and put the baffle straight up and down. This would 45 answer the same purpose but would not give the same bevel or display in the front of the case. Another feature of the baffles causes the cold air currents to shoot down each side of the pan, cutting off any circulation of warm 50 air from coming in contact with the bottom of the pan, which causes much condensation. With the baffles, the warm air shoots upward between the downward cold air current and the wall of the case. All the moisture in the 55 warm air is carried up the hot air flue and condensed on the coils or cold tank above.

I am aware that changes may be made in the details of construction without departing from the spirit of my invention, and within 60 the scope of the appended claim.

What I claim is:

In a refrigerator show case, having a glass front and glass doors at the rear, a mechanical refrigeration means positioned near the 65 top of the case, a drip pan under said means and a baffle plate on each side of and spaced from said means and pan and converging toward each other from the bottom to the top, and also spaced from the front and rear walls 70 of the case, a storage compartment in the bottom of the case, and a perforated display shelf over said compartment whereby warm air passes up to said means between the case walls and baffles and the cold air passes downward between the baffles into the case and storage compartment. 75

In testimony whereof I affix my signature.

CLEMENT V. HILL.
